UNITED STATES PATENT OFFICE

104,309

DESIGN FOR A TEXTILE FABRIC

Mark Turpan, West New York, N. J.

Application April 3, 1937, Serial No. 68,539

Term of patent 3½ years

To all whom it may concern:

Be it known that I, Mark Turpan, a citizen of the United States of America, residing in West New York, county of Hudson, and State of New Jersey, have invented a new, original, and ornamental Design for a Textile Fabric, of which the following is a specification, reference being had to the accompanying drawing, forming part thereof, wherein,

The figure is a plan view of a piece of textile fabric showing my new design.

The design, as shown, shows the exact design as arranged from one edge of the fabric to the other, which design comprises a floral grouped center with contrasting lines at its outer portion, arranged in combination with the split half of the center portion at its outer edges.

I claim:

The ornamental design for a textile fabric, substantially as shown, and described.

MARK TURPAN.
